GUSTAV FRITZ HALANK, OF DRESDEN, GERMANY, ASSIGNOR TO THE FIRM: JOHANN
CARL MÜLLER, OF DRESDEN, GERMANY.

MACHINE FOR AFFIXING LABELS OR THE LIKE.

Application filed July 3, 1924. Serial No. 723,978.

To all whom it may concern:

Be it known that I, GUSTAV FRITZ HALANK, a citizen of Germany, residing at Dresden, Saxony, Germany, have invented 5 certain new and useful Improvements in a Machine for Affixing Labels or the like, of which the following is a specification.

Machines for affixing labels or the like are known in which a vertically movable label 10 pile is applied to a surface coated with adhesive which grips and removes the lowermost sheet of the pile. Moreover, it is known to provide the adjacent ends of two swinging levers with adhesive faces, which 15 grip the lowermost label of the pile at two opposite edges and lead it to the object to be labelled. Such known apparatus is used for labelling bottles where it is sufficient for the ends only of the labels to be coated 20 with adhesive.

As distinguished from this in accordance with the present invention the whole surface of the label is carefully coated with adhesive in order that the label can be applied to a box and will serve as a closing 25 or sealing medium. For this purpose the rocking levers are so arranged that their ends abut and form a substantially continuous adhesive coated face of the size of the 30 labels. The pile is lowered on this face after the face has been coated with adhesive by means of a roller similar to the roller 35 employed in the inking of printing plates. The lowermost label adheres to the adhesive coated face. It is held against the one lever by means of a clamping bar or the like. When the levers are subsequently moved a 40 part of the label is withdrawn from the face of the one lever and the adhesive is thus well distributed thereover. The lever holding the label is then moved further till the 45 free edge of the label comes in contact with the box or the like which has been moved in position during this operation. The label is then gripped by a roller, which is led over the box face to be gummed, and is thus rolled down on the face, the second part of the label being then withdrawn from its lever, so that the adhesive on this 50 portion is also well distributed.

In the accompanying drawing Fig. 1 shows in side view partly in longitudinal section, a machine for applying strips of paper on cigarette boxes and the like.

Fig. 2 is a detail view of a part of the 55 machine.

Figs. 3 to 6 are diagrammatic illustrations to enlarged scale affording an explanation of the modus operandi of the machine.

As shown, the strips are piled in an upright cage 1 loaded by a weight 2 in the usual manner. The cage is secured to an I-shaped member 3 slideable in guides 4. To the pivots 5 mounted on the member 3 is connected by links 6, a lever 8 pivoted at 60 7. This lever carries a roller 9 which with a cam disc 10 engages with a continually rotating shaft 11. This cam disc 10 thus produces a vertically reciprocating motion of the cage 1 containing the pile of strips. 70

At a short distance beneath the pile of strips is arranged a horizontal surface formed of the two parts 12 and 13 (Fig. 3). These surfaces are formed by the ends of abutting rocking levers 14 and 15 which 75 each form one arm of a bell crank lever 16 and 17 (Fig. 1), which swing about the pivots 18 and 11 and are provided at their free ends with rollers 19 and 20.

These rollers bear on cam discs 21 and 22, 80 springs being provided if necessary to ensure contact, which cam discs 21 and 22 are secured to continuously rotating shafts 23 and 24. The cam discs 21 and 22 ensure that the lever arms 14 and 15 will be held 85 in the position shown in thin lines in Fig. 1 during the major portion of the rotation of the shafts 23 and 24, in which the lever ends 14 and 15 abut and thus the two parts 12 and 13 form a connected surface (Figs. 90 3 and 4). Only when the cams on the discs 21 and 22 contact with the rollers 19 and 20 are the lever arms 14 and 15 brought downwards into the separated position shown in Fig. 1.

On the machine arm A is provided an adhesive container 25 into which dips a roller 26 mounted on a continuously rotating shaft 27. The roller takes up adhesive and applies it in known manner to a second roller 28 contacting therewith. A third roller 29 comes intermittently into contact with the roller 28 so that the adhesive is applied to the periphery of this roller in a well distributed condition. The roller 29 100 is pivotally mounted on a horizontal support 30 against the opposite end of which bears a cam disc 31 secured to the shaft 11. 105

A spring (not shown) ensures that the support 30 is drawn continuously against the cam disc. The cam disc imparts to the support 30 with the adhesive-applying roller 29 a reciprocating movement and thus the adhesive roller 29 comes in contact with the horizontal surfaces 12 and 13 whereby the latter is coated with adhesive. The cam discs 10 and 31 are arranged on the shaft 11 in such manner that the pile of strips moves downwards on to the surfaces 12, 13 at the moment when it is coated with adhesive. In consequence the adhesive adheres to the surfaces 12, 13 of the lowermost strip when the pile is again raised.

On the lever arm 15 is arranged a clamping bar 32 secured to a support 33 rotatable about a pivot 34. The support 33 has an extension 35 carrying at its end a roller 36. This roller engages with the cam disc 37 secured to the shaft 11. The cam disc 37 ensures that the clamping bar 32 will fall into the position shown in thin lines in Fig. 1 on to the part 13 of the surface, as soon as the lowermost sheet of the pile has touched the adhesive surface. The clamping bar 32 thus holds the strip on the surface 13 of the lever arm 15 (Fig. 4).

Thereafter the rocking levers 16 and 17 swing outwards until the lever arms 14 and 15 move into the position shown in full lines in Fig. 1. In this swinging movement the strip is withdrawn from part 12 of the surface whereby its left hand half is coated carefully on its lower surface with adhesive and is now carried only by the lever arm 15.

The objects in the present instance, cigarette boxes, are arranged in piles in a cage 38. Beneath this cage passes the upper flight of an endless chain 39 at a distance therefrom corresponding to about the depth of one of the boxes. This chain is led over the two sprockets 40 and 41, of which sprocket 40 mounted on the shaft 42 is continuously rotated.

On the chain are mounted vertical projections 43, at such a distance from one another that a box may be interposed between each pair. On their upper ends the projections 43 are provided with rollers which glide smoothly over the walls of the box.

By means of the chain the boxes are moved into the path of the arm 15 which holds the strip, provided on its lower side with adhesive. Thus the co-operation of the chain with the bell crank lever 17 is such that the box B in question moves into position shown in Fig. 1 when the lever arm 15 has reached its lowermost position (Fig. 5), where the free end of the strip C carried by the arm contacts with the surface of the box. In order now to apply the strip to the surface of the box there is provided a roller

45 mounted at the end of a lever 46 which is rotatably mounted at 47 on the machine frame. This lever carries a roller 48 with which it bears against a cam disc 49 secured to the shaft 23. By means of a spring or the like (not shown) the lever is continuously pressed with its roller 48 against the cam disc 49. The cam disc 49 now presses the lever at the required moment into the position shown in Fig. 1, where the roller 45 bears on the surface of the box B where this face is contacted by the edge of the strip C (Fig. 5). If now the box B moves further the roller 45 rolls the strip over the surface of the box B, the strip being withdrawn from the surface 13 of the lever 15 and thereby coated carefully on its right hand half with adhesive. Previously the cam disc 37 has ensured the removal of the clamping bar 32 so that the strip C can move under the influence of the roller 45. As soon as the strip C is rolled over the surface of the box B all the cam discs, in consequence of suitable formation and adjustment, return to their initial positions so that the operation can re-commence.

The box B coated with the strip now travels forward. At both sides of the box the ends of the strips D project but they are later in known manner pressed by means of brushes E (Fig. 6) against the sides of the box and if desired also with their extreme ends on the bottom of the box. The boxes which now push one another forward pass on to the table F to a delivery outlet G.

The machine is driven from the shaft 50 in such manner that the shaft 42 is driven in the direction of the arrow by means of a belt drive or the like. On the shaft is mounted a pinion 51 which meshes with a pinion 52 on the shaft 27 of the gumming roller 26, and also with the pinion 53 on the shaft 24 of the cam disc 22. This pinion drives the pinion 54 on the shaft 23 of the cam disc 21 which also carries the cam disc 49. The pinion 53 meshes also with the pinion 55 mounted on the shaft 11.

Having now particularly described and ascertained the nature of my said invention and in what manner the same is to be performed, I declare that what I claim is:

1. A method of automatically labelling articles, consisting in applying adhesive to a pair of separable surfaces adapted initially to form a continuous surface, then lowering a pile of labels to cause the lowermost thereof to adhere completely to said surfaces, then separating said surfaces to cause the adhering label to be removed from one of them and brought into contact with the article to be labelled and finally causing said label to be removed from the other surface and to be applied to the article.

2. In a machine for affixing labels or the like to continuously fed articles, the com-

- bination with a vertically reciprocating pile of labels, of a pair of removable members adapted in initial position to receive a label from said pile and to form a continuous surface, means adapted to move over said surface to apply adhesive to the latter prior to the lowering of the label pile, means for moving said members apart after receiving a label, so as to withdraw the latter from the surface of one of said members, bringing it into contact with the article to be labelled, and means for subsequently removing the label from the other member and applying it to the article.
- 5 3. In a machine for affixing labels or the like to continuously fed articles, the combination with a vertically reciprocating pile of labels, of a pair of vertically swinging levers adapted in initial position to receive a label from said pile and to form a continuous 20 surface, means adapted to move over said surface to apply adhesive to the latter prior to the lowering of the label pile, means for clamping the label to one of said members, means for moving said members apart to 25 cause the unclamped portion of the label to be removed from the other member and to be brought into contact with the article to be labelled, means for releasing the clamped portion of the label and means for removing 30 said portion from the first named member and for applying the label to the article.
- 10 In testimony whereof I affix my signature in presence of two witnesses.
- 15 GUST. FRITZ HALANK.
